UNITED STATES PATENT OFFICE.

AUGUSTUS E. DURNER, OF EVANSVILLE, WISCONSIN.

HARROW-DISK SHARPENER.

SPECIFICATION forming part of Letters Patent No. 708,802, dated September 9, 1902.

Application filed February 10, 1902. Serial No. 93,307. (No model.)

To all whom it may concern:

Be it known that I, AUGUSTUS E. DURNER, a citizen of the United States, and a resident of Evansville, in the county of Rock and State 5 of Wisconsin, have invented certain new and useful Improvements in Harrow-Disk Sharpeners; and I do hereby declare that the following is a full, clear, and exact description thereof.

10 My invention has for its object to provide simple, economical, and efficient machines for rapid even sharpening of harrow-disks without removal of the same from their shafts, said invention consisting in certain peculiarities of construction and combination of parts hereinafter particularly set forth with reference to the accompanying drawings and subsequently claimed.

Figure 1 of the drawings represents a front 20 elevation of a harrow-disk-sharpening machine in accordance with my invention having parts thereof broken and in section, as indicated by lines 1 1 in the second figure; Fig. 2, a plan view of the machine, partly 25 broken and in horizontal section, as indicated by line 2 2 in the first figure; and Fig. 3, a vertical transverse section of said machine, indicated by line 3 3 in said first figure.

Referring by letter to the drawings, A indicates each of a pair of parallel beams, spaced apart and connected at their ends by standards B C of cast metal. In practice the frame comprising the beams and standards aforesaid may be set on a bench or trestles or provided with legs. The frame-standard B is provided with a bearing for a live-spindle D, and a tail-screw E is adjustable in bracket C opposite said spindle. The bracket B is also provided with a bearing for a drive-spindle 35 F, that is turned by a crank G or its mechanical equivalent, and a sprocket-wheel H is shown fast on live-spindle D, connected by a link belt I with a sprocket-pinion J, fast on the drive-spindle; but it is practical to substitute spur-gear for the link belt and sprocket-gear. The inner end of the live-spindle is made angular, and a coupling or chuck K, slipped thereon, engages a nut b, that is commonly on an end of a shaft L, upon which a 45 series of harrow-disks M are arranged, the other end of the shaft being engaged by the

point of the tail-screw E aforesaid. It may be found convenient and desirable to provide each machine with a set of interchangeable chucks, designed to fit various sizes of shaft-nuts. One of the beams A is shown provided with longitudinal side guides N for a slide P, that straddles said beam, the inner depending portion of the slide being flanged to catch under the adjacent guide. Dovetailed in the 55 slide P transversely thereof is a plate Q, engaged by the lower end of a swivel-post R, that extends up through a sleeve S, supported on the plate. An adjusting-screw T has the threaded portion thereof engaged with a depending front ear c of plate Q, the inner end of the screw being in the form of a journal upset in a countersunk aperture in the front side of the slide P aforesaid. The shank d of a cutting-tool U engages a vertical slot in 60 post R and diametrically opposite notches in sleeve S, a set-screw V being arranged in the upper outer end of said post to impinge against the tool-shank. The plate Q is shown provided with an eye-lug e, and a lever W is 65 stepped in this lug. An antifriction-roller X is hung in an open swell portion of lever W, and in practice a harrow-disk is caught between the roller and the aforesaid cutting-tool, pressure of said roller being regulated 70 by said lever. The tool-holder, comprising plate Q, post R, sleeve S, and set-screw T, is adjusted on slide P to accommodate the tool U to harrow-disks of various diameters, and said slide being loose longitudinally of the 75 machine automatic compensation is had for irregularities in a rotating disk or wobble of the same on its shaft when caught between said tool and the lever-controlled roller X, whereby spring of said disk is prevented and 80 even cut of the aforesaid tool assured. To change the tool from one to another of a series of harrow-disks on a shaft hung in the machine, the slide P is unhooked from its inner guide and with the tool-holder lifted clear 85 of the machine-frame and replaced in new 90 position.

While I have shown a practical form of a machine embodying my invention, the structural details of same may be varied somewhat without departure from the scope of 95 said invention.

Having thus described my invention, what I claim as new, and desire to secure by Letters Patent, is—

1. A harrow-disk sharpener comprising a frame, means for chucking and rotating a shaft with a series of harrow-disks thereon between standards of the frame, a slide straddling a longitudinal frame-beam in hook connection therewith, a plate guided on the slide in a direction transversely of said frame, means for regulating adjustment of the plate, a post in swivel connection with said plate, a sleeve on the post, a cutting-tool having a shank engaging a vertical post-slot and sleeve-notches, a set-screw in the upper end of said post opposing the tool-shank, a hand-lever for which the aforesaid plate is provided with a step, and an antifriction-roller carried by the lever opposite the cutting-tool.
2. A harrow-disk sharpener comprising a frame, means for chucking and rotating a shaft with a series of harrow-disks thereon between frame-standards, a slide straddling a longitudinal frame-beam in hook connection therewith, a plate guided on the slide in a direction transversely of said frame, an adjusting-screw having a journal end in said slide and its threaded portion engaging an ear of the plate, a post in swivel connection with the aforesaid plate, a sleeve on the post, a cutting-tool having a shank engaging a vertical post-slot and sleeve-notches, a set-screw in the upper end of said post opposing the tool-shank, a hand-lever for which the aforesaid plate is provided with a step, and an antifriction-roller carried by the lever opposite the cutting-tool.

In testimony that I claim the foregoing I have hereunto set my hand at Evansville, in the county of Rock and State of Wisconsin, in the presence of two witnesses.

AUGUSTUS E. DURNER.
